UNITED STATES PATENT OFFICE.

EDGAR SAMUEL LYONS, OF TORONTO, ONTARIO, CANADA, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

WIRE-COILING MACHINE.

1,192,655.

Specification of Letters Patent. Patented July 25, 1916.

Application filed June 22, 1914. Serial No. 846,487.

To all whom it may concern:

Be it known that I, EDGAR SAMUEL LYONS, a British subject, and resident of the city of Toronto, in the county of York and Province of Ontario, Dominion of Canada, have invented certain new and useful Improvements in Wire-Coiling Machines; and I hereby declare that the following is a full, clear, and exact description of the same.

10 My invention relates to a machine for forming spring coils at the ends of two opposite sides of a wire clip and bending the ends of these coils reversely to the direction of their spirals to form attaching members 15 for conveniently securing the clips to a holder and tensioning the coils.

The apparatus by which this is accomplished consists of means for holding a wire blank, and means for coiling two sides of the 20 same, said coiling means including coil shapers, and winders revoluble in one direction for twisting the wire around said shapers for the formation of the spirals, and benders automatically movable lengthwise of the coils, to engage with the ends of the wire when the revolution of the winders is reversed whereby the winders can bend the ends of the coils reversely to the direction of the spirals, for the formation of the 25 attaching members by which the clips are secured to the holder.

For an understanding of my invention, reference is to be had to the following description and to the accompanying drawings, in which:

Figure 1 is a perspective view of the wire coiling machine with the clip bed in a reclined position and a partially formed clip thereon; Fig. 2 is a similar view to Fig. 1, 40 with the clip bed in an upright position to hold the clip during the formation of the coils; Fig. 3 is a detail view of the hook-shaped end of one of the heel benders; Fig. 4 is a detail view of a clip prior to the formation of the coils; Fig. 5 is a view of the clip 45 shown in Fig. 4 after the forming of the coils but prior to the bending of the attaching members reversely to the spirals; and Fig. 6 is a view of the finished clip.

50 Hinged to the standard a is the clip bed b to be turned into either a reclined position as shown in Fig. 1, or into an upright position as shown in Fig. 2, and projecting from opposite sides of the standard a , parallel to

the face of the bed b , are two coil shapers c . 55 Opposed to each coil shaper is a winder d fixed on a crank axle e , each winder d and its axle e having a central bore f to receive its respective coil shaper c therein. The axles e are mounted to slide lengthwise in 60 bearings g and their outer ends are provided with crank handles h by which the winders are rotated. On the bed b are retaining pins i by which the wire blank m is held in position during the formation of the coils j . 65 Fulcrumed to the standard a , above the coil shapers c , are the benders k tensioned by a spring l , the benders k being provided with hook-shaped ends l' located above the coil-shapers c and movable toward and away 70 from the standard a .

In the operation of the machine the clip bed b is lowered into the reclined position shown in Fig. 1, and the wire blank m , shown in Fig. 4, is placed upon the bed 75 around the retaining pins i with the ends of the wire blank located above and extending beyond the coil shapers c . When the blank is correctly placed upon the bed b , the latter is turned from the position shown in Fig. 1 80 to that shown in Fig. 2, in which position the wire blank is securely clamped between the standard and the bed. When the bed is in the position shown in Fig. 2, the winders d are moved in the direction of the standard 85 until their winding pins d' engage the sides of the wire blank m . The winders d are then rotated in one direction to twist the sides of the wire blank m into coils j around the coil-shapers c , the turning of the winders in this direction being continued until the formation of the coils is completed, as shown in Fig. 5. When the winders d are moved in the direction of the standard a 90 they engage the hook-shaped ends l' of the benders k and move these hook-shaped ends against the standard a , or if the standard is grooved, as shown at a' in Fig. 1, they move the hook-shaped ends l' into these grooves, so that they will not interfere with the formation of the initial spirals of the coils j 95 during the rotation of the winders in the coil-forming direction. As the spirals are formed the coils j automatically press the winders in the direction of the bearings g , 100 and as the winders move in this direction, the hook-shaped ends l' of the benders k , under the influence of the spring l , auto-

matically follow them and occupy the position shown in full lines in Fig. 1, so that when the formation of the coils is completed their hook-shaped ends l' will be positioned 5 to engage the ends m' of the wire blanks m when the rotation of the winders is reversed to form the attaching members o , which, as shown in Fig. 6, are reversed with respect to the direction of the spirals.

10 To enable the spirals to readily clear the benders during the formation of the coils the sides of the hook-shaped ends l' opposed to the direction of the spirals are beveled, as shown at l'' , Fig. 3, and when the 15 spirals engage these bevels, during the formation of the coils, they move the benders inward toward the standard a and pass them without difficulty. To securely hold the ends of the wire coils during the formation 20 of the attaching members, the hook-shaped ends l' have curved recesses l^3 to receive the ends of the coils during the reverse rotation of the winders.

To hold the wire blank against the coil 25 shapers c while the clip bed is being turned from a reclined position to an upright position the standard a is provided with retaining pins c' to engage the top of the blank sides; and to maintain the clip bed in its 30 upright position until lowered again, the standard a is provided with a spring latch z which engages with a keeper y attached to the clip bed.

Having thus fully described the nature of 35 my invention, what I claim as new and desire to secure by Letters Patent, is:

1. A wire coiling machine comprising means for holding a wire blank, means for coiling the ends of said blank, and automatically positioned means coöperating 40 with the coiling means to bend the ends of the coils reversely to the direction of the spirals.

2. A wire coiling machine comprising 45 means for holding a wire blank, means for coiling two sides of the same, said coiling means including coil shapers and winders revolvable in one direction for twisting the wire around said shapers for the formation of the coils, and benders automatically movable lengthwise of the coils to engage with the ends of the wire when the revolution of the winders is reversed whereby the winders 50 can bend the ends of the coils reversely to the direction of the spirals for the formation of the attaching members by which the coils are tensioned and secured to a holder.

3. A wire coiling machine comprising 60 means for holding a wire blank and means for coiling two sides of the same, said coiling means including coil shapers and wind-

ers revolvable in one direction for twisting the wire around said shapers for the formation of the coils, and spring tensioned benders 65 fulcrumed to the apparatus, having hook-shaped ends automatically movable lengthwise of the coils to engage with the ends of the wire when the revolution of the winders is reversed, whereby the winders 70 can bend the ends of the coils over said hook-shaped ends of the benders reversely to the direction of the spirals for the formation of the attaching members by which the coils are tensioned and secured to a holder. 75

4. A wire coiling machine comprising means for holding a wire blank and means for coiling two sides of the same, said coiling means including coil shapers and winders revolvable in one direction for twisting the wire around said shapers for the formation of the coils, and spring tensioned benders 80 fulcrumed to the apparatus, having hook-shaped ends automatically movable lengthwise of the coils to engage with the ends of the wire when the revolution of the winders is reversed, whereby the winders can bend the ends of the coils over said hook-shaped ends of the benders reversely to the direction of the spirals for the formation 85 of the attaching members by which the coils are tensioned and secured to a holder, the sides of said hook-shaped ends opposed to the direction of the spirals being beveled so that the wire will displace the benders 90 and pass them without difficulty during the formation of the coils.

5. A wire coiling machine comprising means for holding a wire blank, means for coiling it, and benders automatically movable lengthwise of the coils to engage with the ends of the blank when the revolution 100 of the coiling means is reversed.

6. A wire coiling machine comprising means for holding a wire blank, means for forming the coils, and benders pivoted to the machine to automatically follow the increasing length of the coils and engage with the ends of the blank when the revolution 105 of the coiling means is reversed.

7. A wire coiling machine comprising means for holding a wire blank, means for forming the coils, and benders pivoted to the machine to automatically follow the increasing length of the coils and engage with the ends of the blank when the revolution 110 of the coiling means is reversed, each of said benders having a hook-shaped end with a wire retaining recess therein.

Toronto, April 30th, A. D., 1914.
